UNITED STATES PATENT OFFICE

HARRY G. FRANCIS, OF RUSHVILLE, INDIANA

GLUE SPREADER

Application filed April 18, 1930. Serial No. 445,244.

My invention is concerned with glue-spreading machines of the type in which a rotatable roll dips into a glue-pan and, by its rotation, carries glue on its surface from the glue-pan to the point where it is to be applied to a board or other article. In certain instances, particularly where thick, viscous glues are used, the tendency of the glue to adhere to the roll causes the glue to be carried from one side of the glue-pan to the other; and the pan, on the side toward which the roll carries the glue, must therefore be enlarged in order to prevent the glue from spilling over the edges of the pan.

It is the object of my invention, to provide in such a machine means which will tend to prevent the transfer of the glue from one side of the glue-pan to the other, and it is a further object of my invention to produce a means which will accomplish this result without interfering with the flow of glue in the reverse direction under the influence of gravity.

In carrying out my invention I provide for the glue-spreading roll a thin shield which extends substantially for the length of the roll and which is in closely spaced relation thereto over a considerable portion of that part of the roll-circumference which is immersed in the glue. Such shield is desirably spaced from the glue-pan in order to provide a passage through which any glue carried to one side of the pan by the rotation of the roller may return under the influence of gravity to the other side of the pan.

The accompanying drawings illustrate an embodiment of my invention: Fig. 1 is an end elevation of a glue-spreading machine with parts of the supporting frame broken away to show the construction more clearly; Fig. 2 is a fragmental front elevation of the machine, again with certain parts broken away; and Fig. 3 is a vertical section through the glue-pan and shield in a plane transverse to the axis of the glue-spreading roll.

My invention is not limited in its application to any particular form of glue-spreading machine, that illustrated in the drawings being but one type of device with which my invention may be used. The machine shown

in the drawings comprises a frame 10 which supports two parallel horizontal glue-spreading rolls 11 and 12, the roll 11 being mounted above the roll 12. The two glue-spreading rolls have respectively associated with them glue-pans 13 and 14, the glue-pan 14 for the lower roll 12 being mounted below such roll and preferably being vertically adjustable as by adjusting mechanism 15 which is more fully described in my co-pending application Serial No. 421,934, filed January 20, 1930.

Means (not shown) are provided for rotating the two rolls 11 and 12 in the respective directions indicated by the arrows in Fig. 1, the articles to which glue is applied being passed between the rolls, and glue being carried by the rolls from the glue pans and deposited upon the article. The amount of glue carried to the article is preferably limited as by scraper rolls 16.

As previously stated, the rotation of the roll 12 tends to carry glue from the left-side of the tank 14 (Fig. 1) to the right-hand side of such tank; and if the glue is thick and viscous, substantially all of it may be thus displaced. To prevent this displacement of the glue I employ the shield 20 which is conveniently formed of sheet-metal in arcuate cross-section and extends for the full length of the roll 12. Desirably, the shield 20 extends from a point about the level of the glue, on that side of the roll which moves upward, to and slightly beyond the lowermost point of the roll, as is clear from Fig. 3. The lower portion of the shield 20 may be in contact with the roll 12 or may be spaced a slight distance therefrom; and preferably, the distance between the shield and the surface of the roll increases in the direction of roll-rotation, as is also clear from Fig. 3.

For the purpose of mounting the shield 20 in desired position, I may provide at each end of the roll 12 a support 21 to which the shield 20 is secured as by means of screws 22. The supports 21 are conveniently mounted through the medium of brackets 23 which are secured to the frame 10 of the machine and have horizontally projecting flanges 24 across the tops of which the supports 21 respectively extend. Hand-screws 25 may be employed to

100

secure the supports to the bracket-flanges 24.

It will be apparent that the shield 20, for a considerable portion of the circumference of the roll 12, prevents frictional contact of such roll with the body of the glue in the pan 14. Since the tendency of the roll to displace glue from one side of the pan to the other depends to a large extent upon the area of roll-surface in contact with the body of the glue, the presence of the shield 20 tends to prevent displacement of the glue by rotation of the roll. The shield 20 should be mounted in such a position that a space is provided between it and the bottom of the pan 14 in order to permit the free return of glue under the influence of gravity from the right-hand side of the tank to the left-hand side. It will be noted that by extending the shield in the direction opposite to that in which the lower surface of the roll is moved the glue in the comparatively narrow passage between the shield and the bottom of the pan is not subjected to any frictional contact with the roll which would prevent its free flow toward the left.

The shield 20, being supported from the frame 10, remains in constant position relative to the roll 12 irrespective of any vertical adjustment of the pan 14.

The shield 20 shaped and mounted as above set forth is the preferred form of the flow-retarding or flow-preventing means, but other forms of flow-retarding means are within my invention, considered broadly. Thus, it is not necessary that the flow-retarding means be a single member nor is it essential that it be as thin radially of the roll as the shield 20. Further, while I prefer to support the flow-retarding means from the frame when the glue pan is vertically adjustable, other arrangements for its support are possible; and where the glue pan is not vertically adjustable, the flow-retarding means may be supported from it.

I claim as my invention.

1. In a glue-spreading machine having a rotatable spreader roll and a glue-pan for containing a supply of glue into which said roll dips, a shield located closely adjacent a portion of that part of the surface of the roll which is immersed in the glue, said shield being spaced from the glue pan and extending in a direction opposite to that in which the roll rotates from a point near the surface of the glue to and beyond the lowermost point of the roll surface, said shield being arranged so that the distance between it and the roll surface gradually increases in the direction of roll-rotation.

2. In a glue-spreading machine having a rotatable spreader roll and a glue-pan for containing a supply of glue into which said roll dips, a shield located closely adjacent a portion of that part of the surface of the roll which is immersed in the glue, said shield

being spaced from the glue-pan and extending in a direction opposite to that in which the roll rotates from a point near the surface of the glue to near the lowermost point of the roll surface, said shield at the latter point being closer to the roll than at other points.

3. In a glue-spreading machine having a rotatable spreader roll and a glue-pan for containing a supply of glue into which said roll dips, a shield located closely adjacent a portion of that part of the surface of the roll which is immersed in the glue, said shield extending in a direction opposite to that in which the roll rotates from a point near the surface of the glue to and beyond the lowermost point of the roll surface, said shield being arranged so that the distance between it and the roll surface gradually increases in the direction of roll-rotation.

4. In a glue-spreading machine having a rotatable spreader roll and a glue-pan for containing a supply of glue into which said roll dips, a shield located closely adjacent a portion of that part of the surface of the roll which is immersed in the glue, said shield extending in a direction opposite to that in which the roll rotates from a point near the surface of the glue to near the lowermost point of the roll surface, said shield at the latter point being closer to the roll than at other points.

5. In a glue-spreading machine, the combination of a frame, a rotatable spreader roll mounted in said frame, a glue-pan below said spreader roll and adapted to contain a supply of glue into which said roll may dip, means for adjusting the vertical position of said pan relative to said roll, and a shield supported from said frame and located adjacent a portion of the immersed surface of said roll to retard movement of the body of the glue under the influence of roll rotation.

6. In a glue-spreading machine, the combination of a frame, a rotatable spreader roll mounted in said frame, a glue-pan below said spreader roll and adapted to contain a supply of glue into which said roll may dip, means for adjusting the vertical position of said pan relative to said roll, and means supported from said frame for retarding movement of the body of the glue under the influence of roll rotation.

7. In a glue-spreading machine, the combination of a frame, a rotatable spreader roll mounted in said frame, a glue-pan below said spreader roll and adapted to contain a supply of glue into which said roll may dip, means for adjusting the vertical position of said pan relative to said roll, and means supported from said frame for separating a portion of the immersed roll-surface from contact with the body of the glue in said pan.

8. In a glue-spreading machine, the combination of a frame, a rotatable spreader roll

mounted in said frame, a glue-pan below said spreader roll and adapted to contain a supply of glue into which said roll may dip, means for adjusting the vertical position of said pan relative to said roll, and means for retarding movement of the body of the glue under the influence of roll rotation, said last-named means being supported independently of said pan whereby it may remain in fixed position relative to the roll when the pan is adjusted.

9. In a glue-spreading machine, the combination of a frame, a rotatable spreader roll mounted in said frame, a glue-pan below said spreader roll and adapted to contain a supply of glue into which said roll may dip, means for adjusting the vertical position of said pan relative to said roll, and means for separating a portion of the immersed roll-surface from contact with the body of the glue in said pan, said last-named means being supported independently of said pan whereby it may remain in fixed position relative to the roll when the pan is adjusted.

25 10. In a glue-spreading machine having a rotatable spreader roll and a glue-pan for containing a supply of glue into which said roll dips, a shield located closely adjacent a portion of that part of the surface of the 30 roll which is immersed in the glue, said shield extending in a direction opposite to that in which the roll rotates from a point near the surface of the glue to near the lowermost point of the roll surface, said shield being in 35 contact with said roll near said last mentioned point.

11. The invention set forth in claim 10 with the addition that the upper edge of said shield is spaced from the roll.

40 12. In a glue-spreading machine having a rotatable spreader roll and a glue-pan for containing a supply of glue into which said roll dips, a shield for separating a portion of the immersed roll-surface from contact with the body of glue in the pan, said shield being supported independently of said pan.

45 13. In a glue-spreading machine, the combination of a frame, a glue-pan adapted to contain a supply of glue, a rotatable glue-applying roll arranged to dip into said glue supply and to elevate glue to the point at which it is to be applied, a member in contact with the glue-applying surface of said roll for preventing the roll from moving an excess of glue toward the point of application, and means for adjusting the vertical position of said pan, said member being supported independently of said pan whereby its relation to said roll will not be changed by 50 pan-adjustment.

55 In witness whereof, I have hereunto set my hand at Indianapolis, Indiana, this 14th day of April, A. D. one thousand nine hundred and thirty.

60 HARRY G. FRANCIS.
